UNITED STATES PATENT OFFICE.

LOUIS N. D. WILLIAMS, OF OGONTZ, PENNSYLVANIA, ASSIGNOR TO SCOTT & WILLIAMS,
INCORPORATED, OF CAMDEN, NEW JERSEY, A CORPORATION OF NEW JERSEY.

KNITTING-MACHINE NEEDLE.

1,015,108.

Specification of Letters Patent.

Patented Jan. 16, 1912.

Application filed September 19, 1910. Serial No. 582,697.

To all whom it may concern:

Be it known that I, LOUIS N. D. WILLIAMS, a citizen of the United States, residing in Ogontz, Montgomery county, Pennsylvania, have invented certain Improvements in Knitting-Machine Needles, of which the following is a specification.

The object of my invention is to provide an effective pivot construction for the swinging needles employed in certain types of knitting machines, for instance in that type of machine shown in the U. S. Letters Patent of Robert W. Scott, No. 834,763, dated October 30, 1906. This object I attain in the manner hereinafter set forth, reference being had to the accompanying drawing, in which—

Figure 1 represents, disconnected from one another, the parts of a needle of the type to which my invention relates; Fig. 2 represents the parts of the needle applied to one another but not secured together; Fig. 3 shows the needle in its finished condition; Fig. 4 is a transverse section on the line 25 *a—a*, Fig. 3; Fig. 5 is a transverse section on the line *b—b*, Fig. 3, and Fig. 6 is a view similar to Fig. 3, but illustrating a modified construction of the needle in accordance with my invention. Figs. 4 and 5 are on a 30 larger scale than the remaining figures of the drawing.

Heretofore needles such as those to which my invention relates have been provided with a segmental bend in the stem of the needle, to constitute a pivot member, but in making these needles it is very difficult to locate the pivot bend in accurate relation to the needle and to that end of the needle stem on which the cams act to impart movement thereto. In carrying out my present invention, therefore, I have provided a pivot member which can be accurately adjusted on the stem of the needle and can then be secured to said stem beyond risk of displacement thereon. This may be accomplished by soldering the pivot member to the stem of the needle, but I prefer to dispense with the use of solder or other extraneous means for effecting the desired connection.

50 In carrying out my invention I use for the pivot member of the needle a block 1, preferably circular, this block having in one

of its faces a transverse groove 2, of such width that the stem 3 of the needle will fit snugly therein, and of such depth that the 55 side walls of the groove will project to some extent above the face of the needle stem when the latter has been seated upon the base of the groove. By means of a suitable positioning gage the block 1 is first disposed 60 upon the stem of the needle in its proper relation to the needle 4 and to the end 5 of the needle stem upon which act the cams for imparting swinging movement to the needle, and the block is then secured to the stem. 65 This may be done by soldering or brazing together the needle stem and block, but I prefer to effect the connection without the use of solder by applying pressure to the grooved face of the block upon one or both 70 sides of the groove, preferably upon both sides, so as to displace the metal acted upon and cause a portion of it to flow over the stem of the needle and thereby confine the latter so firmly in the groove of the block as 75 to not only prevent it from being forced out of the said groove but also to prevent any longitudinal movement of the block upon the needle stem. In the needle shown in the drawing pressure has been applied to the 80 face of the block at two separated points on each side of the groove, thereby displacing the metal at these points and causing said displaced metal to form fins 6, which overlap the stem of the needle, as shown in Fig. 85 5. In order to aid the displaced portions of the metal in the performance of their intended function, the needle stem is preferably notched in those portions where the fins 6 engage it, such notches being shown at 90 7 and said notches being preferably tapered or beveled, as shown in Fig. 5, whereby, when the displaced metal flows over the stem of the needle the inclined bases of the notches will act as wedges and the needle stem will 95 be forced firmly into contact with the base of the groove 2.

While I always prefer, in carrying out my invention, to use the circular block 1, I may, in some cases, adopt the construction shown 100 in Fig. 6, in which the block 1^a has formed upon it a stem 3^a for the action of the cams whereby the swinging movements are imparted to the needle, the latter having a

short stem 3^b which is secured to the block 1^a by displacement of part of the metal of the latter, as before described.

I claim:

5. 1. A knitting machine needle having a pivot member consisting of a circular block secured to the stem of the needle.
2. A knitting machine needle having a pivot member consisting of a circular block 10 with transverse groove therein, the stem of the needle being secured in said groove.
3. A knitting machine needle having a pivot member consisting of a block with transverse groove which receives the stem 15 of the needle, said stem being secured in the groove by a displaced portion of the metal of the block.
4. A knitting machine needle having a pivot member consisting of a block with 20 transverse groove which receives the stem of the needle, said stem being secured in the groove by a displaced portion of the metal of the block on each side of the groove.
5. A knitting machine needle having a pivot member consisting of a block with 25 transverse groove which receives the stem of the needle, said stem being secured in the groove by a displaced portion of the metal of the block, said displaced metal overlapping 30 the stem of the needle.
6. A knitting machine needle having a pivot member consisting of a block with transverse groove which receives the stem of the needle, said stem being secured in the 35 groove by a displaced portion of the metal of the block on each side of the groove, said displaced portions of the metal of the block overlapping the stem of the needle on each side of the same.
40. 7. A knitting machine needle having a notched stem, and a pivot member consisting of a block grooved to receive said stem and having portions of the metal of which it is composed displaced so as to engage the 45 notched portions of the stem.
8. A knitting machine needle having a stem with notches at each side of the same, and a pivot member consisting of a block having a groove for the reception of the 50 needle stem, portions of the metal of which the block is composed being displaced so as to engage the notched portions of the stem.
9. A knitting machine needle having a stem with beveled notches therein, and a

pivot member consisting of a block having 55 a groove for the reception of the needle stem, displaced portions of the metal of the block engaging the notched portions of the stem, and by pressure upon the inclined bases of the notches forcing said stem into 60 contact with the base of the groove.

10. A knitting machine needle comprising a stem having the needle at one end and at the other end a portion for being acted upon by the cams whereby swinging movement is 65 imparted to the needle, said needle stem having, at an intermediate point, a pivot member consisting of a circular block to which the stem of the needle is secured.

11. A knitting machine needle comprising 70 a stem having the needle at one end and at the other end a portion for being acted upon by the cams whereby swinging movement is imparted to the needle, said needle stem having, at an intermediate point, a pivot member 75 consisting of a circular block with transverse groove therein, the stem of the needle being secured in said groove.

12. A knitting machine needle comprising a stem having the needle at one end and at 80 the other end a portion for being acted upon by the cams whereby swinging movement is imparted to the needle, said needle stem having, at an intermediate point, a pivot member 85 consisting of a block grooved to receive the needle stem, which is retained in position in such groove by means of a displaced portion or portions of the metal of which the block is composed.

13. A knitting machine needle having a 90 stem with pivot member thereon comprising a block having a groove for the reception of the needle stem, and, on either side of said groove, spaced fins overlapping and retaining said needle stem.

14. A knitting machine needle having a stem with pivot member thereon comprising a block having a groove for the reception of the needle stem, and, on each side of said groove, spaced fins overlapping and retaining 95 said needle stem.

In testimony whereof, I have signed my name to this specification, in the presence of two subscribing witnesses.

LOUIS N. D. WILLIAMS.
